UNITED STATES PATENT OFFICE.

WEBSTER C. ESTES, OF BROOKLYN, NEW YORK.

DESIGN FOR A WOODEN BOX.

SPECIFICATION forming part of Design No. 24,035, dated February 12, 1895.

Application filed October 31, 1894. Serial No. 527,580. Term of patent 7 years.

To all whom it may concern:

Be it known that I, WEBSTER C. ESTES, a citizen of the United States, residing at Brooklyn, in the county of Kings and State of New York, have invented and produced a new and original Design for a Wooden Box, of which the following is a specification.

In the drawings I have presented my design by an elevation and partial section, Figure 1, and a plan, Fig. 2.

The general configuration of the box is round and the leading features of my design consist in the beaded top and bottom edges and intermediate plain parallel sided portion.

15 The design of the cover A of the box comprises the plain horizontal top portion a, the beads b c at the upper edge of the cover and the plain parallel side faces d. The beads b c are of the same half-round conformation but

of unequal size, the larger half round bead b ²⁰ being at the upper edge of the cover.

The design of the body portion B comprises the plain parallel side faces e that align with the faces d of the cover, the beads f h of half round conformation at the lower edge, and ²⁵ the flat bottom i. The beads f h are of like half round conformation but of unequal size the larger half round bead h being at the bottom edge.

What I claim is—

30 The design for a wooden box substantially as shown and described.

Signed by me this 29th day of October, A. D. 1894.

WEBSTER C. ESTES.
